D. CAVICCHIOLI

TOY SHOOTER

Filed Feb. 7, 1923

UNITED STATES PATENT OFFICE.

DANTE CAVICCHIOLI, OF NEW YORK, N. Y.

TOY SHOOTER.

Application filed February 7, 1923. Serial No. 617,451.

To all whom it may concern:

Be it known that I, DANTE CAVICCHIOLI, a citizen of the United States, and residing at New York, in the county of New York and State of New York, have invented certain new and useful Improvements in Toy Shooters, of which the following is a specification, such as will enable those skilled in the art to which it appertains to make and use the same.

This invention relates to toy shooters or devices designed to advance balls, rings or the like in the playing of games of various kinds and classes, and particularly in advancing such bodies to strike predetermined objects, and the object of the invention is to provide a device of the class specified which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a sectional side view of one form of shooter device which I employ;

Fig. 2 a plan view of a device shown in Fig. 1 with part of the construction broken away;

Fig. 3 a section on the line 3—3 of Fig. 1;

Fig. 4 a view similar to Fig. 1 but showing a modified form of shooter device;

Fig. 5 a plan view of the device shown in Fig. 4 with part of the construction broken away;

Fig. 6 a side view of a combination of the shooter devices shown in Figs. 1 to 5 inclusive;

Fig. 7 a side view of another modified form of shooter; and,

Fig. 8 a section on the line 8—8 of Fig. 7.

In Figs. 1 and 2 of the drawing I have shown one form of my improved shooter device comprising a handle portion 10 which is apertured to receive a rod 11, the front end of which is provided with a head 12. Centrally of the rod 11 is a radially extending trigger portion 13 inwardly of which a coil spring 14 is mounted on said rod and serves to advance the same when

the trigger is actuated. The handle member 12 is provided at its front end with a cross head 15 through which the rod 11 passes, and that portion of the handle member of the shooter is hollow and comprises side plates 16 which project beyond the cross head 15 to form a receiver 17 for a ball or similar member 18.

Slidably mounted on the plate 16 is a sleeve 19 which is apertured as indicated at 20 to lock the trigger member 13 against movement, and this sleeve serves as a safety lock for the shooter, and one of the side plates 16 is also apertured as shown at 21 to normally hold the trigger as well as the rod 11 in an inoperative or retarded position as shown in Fig. 3 of the drawing.

Pivottally mounted to the cross head 15 is a door member 22 which extends into the receiver 17, which serves to retain the ball against accidental displacement in the receiver 17. The receiver 17 is also provided with inwardly directed projections 23 which limit the upward movement of the door member.

In the use of the shooter shown in Figs. 1, 2 and 3, the advancing rod 11 is moved into the position shown in Fig. 1 and retained in such position by the trigger member 13, after which a ball is placed in the receiver by opening the door 22 and the shooter is ready for use, and by disengaging the trigger member 13 from the aperture 21 the rod 11 will be advanced through the shooter device and the head 12 of the rod will advance the ball 18 through the receiver 17 to any desired object which it is desired to strike.

In Figs. 4 and 5 of the drawing I have shown a modified form of shooter which is designed particularly for advancing ring-like bodies 24 and, in practice, said bodies are provided with a notch 25. With this shooter I provide a handle member 26 on the opposite sides of which are mounted spring members 27, the free ends of which project beyond the handle member and are beaded as shown at 28 and at the opposite sides of the handle member are other spring member 29 and 30, the spring member 29 being provided with an offset substantially semi-circular head 31, while the spring

member 30 is provided with a projecting lip 32. In the use of the shooter shown in Figs. 4 and 5 the notch 25 of the ring body is placed upon the projection 32 of the 5 spring 30 and the ring body is then forced inwardly between the spring members 27 and beneath the curved end 31 of the spring 29, and to advance to discharge the ring from the shooter the spring members 29 and 10 30 are depressed by a thumb and finger of the hand to advance said ring body over a floor or through the air in playing a game of any kind or class.

In Fig. 6 I have shown a shooter in which 15 the shooter device shown in Figs. 1 and 2 is provided at one end of a handle member, while the shooter device shown in Figs. 4 and 5 is provided at the other end thereof thus providing a shooter device capable 20 of advancing two different kinds or shapes of bodies, namely, a ball or ring body.

In Figs. 7 and 8 of the drawing, I have shown a modified form of shooter for advancing ring bodies in which two jaw members 33 and 34 are pivoted together at one 25 end as shown at 35, said jaw members being substantially U-shaped in cross section, and one of said jaw members being provided with a part 36 encircling the other of said 30 jaw members to limit the separation of said jaw members and a spring 37 is placed between the jaw members to normally hold the same in an extended position. The other end portion of the jaw member 34, or the 35 cross head thereof, is pressed inwardly to form a keeper 38 which engages the notch 25 in the ring body 24 and the free end of the other jaw member 33 is provided with a curved spring member 39 similar to the 40 spring member 31, and the use of the shooter device shown in Fig. 7 will be the same as the shooter shown in Figs. 4 to 6 inclusive, it being understood that the jaw members 33 and 34 are pressed together in the 45 advancement of the ring body 24.

It will be noted in Figs. 4 and 5 of the drawing that I employ an adjustment screw 40 at the outer end of the handle member and the object of this screw is to regulate 50 and adapt the device for use in advancing ring bodies of various sizes within certain limits. It will be understood that when a smaller ring body is used the screw head is moved outwardly.

It will be understood that my invention 55 is not necessarily limited to the specific form and construction of the separate shooters herein shown and described, nor to the use of said shooters in advancing a body of any specific shape or form, and various changes 60 in and modifications of the construction herein shown and described may be made, within the scope of the appended claims, without departing from the spirit of my invention 65 or sacrificing its advantages.

Having fully described my invention, what I claim as new and desire to secure by Letters Patent, is:—

1. A shooter device of the class described comprising a handle member provided at 70 one end with means for receiving a spherical member, a spring actuated rod mounted in the handle member and adapted to advance the spherical member through the shooter device, and the other end portion of said handle member being provided with means for retaining a ring body in connection therewith, and means whereby said body may be advanced.

2. A shooter device of the class described 80 comprising a handle member, means for supporting a ring body in connection with one end portion thereof, and means whereby the movement of said supporting means will advance and discharge said ring body from the shooter device, said supporting means comprising a part adapted to engage a recess in the ring body.

3. A shooter device of the class described 90 comprising a handle member provided at one end with a pair of oppositely disposed spring members between which a ring body is adapted to be placed, and another pair of oppositely disposed spring members adapted to engage the periphery of a ring body and by means of which said ring body may be discharged from said shooter device.

4. A shooter device of the class described 100 comprising a handle member provided at one end with a pair of oppositely disposed spring members between which a ring body is adapted to be placed, another pair of oppositely disposed spring members adapted to engage the periphery of a ring body and by means of which said ring body may be discharged from said shooter device, and one of said last named spring members being provided with a part adapted to engage a recess in a ring body.

5. A shooter device of the class described 110 comprising a handle member provided at one end with a pair of oppositely disposed spring members between which a ring body is adapted to be placed, another pair of oppositely disposed spring members adapted to engage the periphery of a ring body and by means of which said ring body may be discharged from said shooter device, one of said last named spring members being provided with a part adapted to engage a recess in a ring body, and the other of said spring members being curved to correspond with the curvature of the ring body.

6. A shooter device of the class described 120 comprising a handle member provided at one end with a pair of oppositely disposed spring members between which a ring body is adapted to be placed, another pair of oppositely disposed spring members adapted to engage the periphery of a ring body and 125

by means of which said ring body may be discharged from said shooter device, one of said last named spring members being provided with a part adapted to engage a recess in a ring body, the other of said spring members being curved to correspond with the curvature of the ring body, and means

mounted in the handle member for adjusting the shooter device to large or small ring bodies.

In testimony that I claim the foregoing as my invention I have signed my name this 5th day of Feb. 1923.

DANTE CAVICCHIOLI.
